UNITED STATES PATENT OFFICE

HARRY CAMBERS, OF LONDON, ENGLAND, ASSIGNOR TO ERNEST HORATIO LUDLOW,
OF MORTLAKE, ENGLAND

PULVERIZED FUEL BURNER

Application filed March 2, 1928, Serial No. 258,626, and in Great Britain March 3, 1927.

This invention relates to pulverized fuel burners of the kind embodying a plurality of spirally disposed longitudinally adjustable vanes mounted within the barrel of the burner in the path of the main fuel and air stream. An object of the present invention is to provide a construction of burner of this nature in which a wide range of control of the length of flame can be obtained, varying from 5 a relatively short flame with great lateral spread suitable for short furnaces of large area, to a long more or less cylindrical flame projected to a considerable distance. In order to utilize fully the centrifugal effect 10 of the whirling motion imparted to the mixture by the vanes there should be little or no constraint imposed on the whirling mixture by any surrounding portion of the barrel after the mixture has left the ends of the 15 vanes so that the barrel should not project to any substantial extent beyond the front discharge ends of the vanes when the latter are at the extremity of their forward adjustment. On the other hand the long flame is obtained 20 by confining the whirling stream of mixture within the barrel for some distance in front 25 of the ends of the vanes.

A further object of my invention is the provision of a pulverized fuel burner of the kind 30 above referred to wherein the range of relative adjustment of the burner barrel and the spirally disposed vanes is such that in the extreme forward position of the vanes their front ends lie at or close to the outlet end of 35 the barrel the other extremity of adjustment being substantially in rear thereof, and that portion of the barrel within the range of adjustment being substantially uniform in cross section.

40 Two forms of construction, by way of example, are illustrated in the accompanying drawings, in which:—

Fig. 1 is a front elevational view of a burner having longitudinally slidable but non-rotative vanes.

Fig. 2 is a plan view partly in section, and

Fig. 3 a vertical longitudinal section of the same:

A is a burner cylinder or barrel provided 50 with a rear end wall B through which enters

the axial inlet pipe C for the mixed fuel and air under pressure. Slidable longitudinally inside the cylinder or barrel A is a truncated conical member D carrying a number of spiral vanes E disposed in the path of the mixed fuel and air issuing from the inlet pipe C which, as will be seen, enters the smaller end of the cone D. The latter is provided with a pair of bosses F into which are screwed rods G which pass through the rear wall B and are pivotally attached to the forked ends of a lever H pivoted to a bracket I secured to the rear wall B. Surrounding the cylinder or barrel A is a conical casing J to which air additional to that entering through inlet C 65 and under pressure may be supplied through connections K controlled by valves L, the air being delivered through the annular opening M surrounding the outlet of the burner.

The spiral vanes E impart a rotary motion 70 to the mixed fuel and air, bringing about a more intimate mixture thereof and delivering a whirling flame from the outlet of the burner. The length of this flame is controlled by moving the vanes longitudinally by means of the lever H, a long flame being produced by sliding the vanes rearwardly towards the inlet pipe C from a position where the discharge ends of the vanes substantially coincide with the discharge end of the barrel 75 or cylinder A to a position further back within the barrel so that the gases are constrained by the cylinder or barrel A and projected 80 more or less axially.

When, however, the vanes are moved forwardly toward the mouth or discharge end of the cylinder or barrel A there is a large lateral spread of the material issuing from the discharge end of the cylinder or barrel 85 due to the centrifugal effect of their whirling motion, and a short, broad flame is produced.

Besides the advantage of very complete control of the length of flame, the burner of the present invention is free from the liability of clogging or becoming obstructed by deposit of fuel, ash, or dust inside the burner, since by moving the vanes quickly longitudinally back and forth a few times or by bringing the end of the coned member D sharply 90

100

into contact with the rear wall B of the burner, the obstructing material may be shaken loose and blown out of the burner.

In carrying my invention into practice it is to be understood that I may provide an alternative form of construction in which the vanes are fixed and the barrel or cylinder surrounding them axially movable, so as to obtain the requisite amount of relative axial movement between the vanes and the barrel, the outlet or discharge ends of the vanes and the barrel being substantially coincident in one extreme position of such relative movement.

15 What I claim is:—

1. A pulverized fuel burner comprising a cylindrical barrel, a single inlet pipe for the fuel and air mixture entering axially at one end of the barrel and projecting to a certain distance therein, a truncated conical member having its smaller end surrounding the projecting portion of the inlet pipe and its larger end making a sliding fit with the inside of the barrel, a plurality of spiral vanes secured to said conical member so as to be slidable within the barrel from a position in which the front ends of said vanes substantially coincide with the outlet end of the barrel to produce a relatively short broad flame to a position farther back in the barrel to produce a relatively longer narrower flame and means for effecting such sliding movement from outside the burner barrel.

2. A pulverized fuel burner comprising a cylindrical barrel, a single inlet pipe for the fuel and air mixture entering axially at one end of the barrel and projecting to a certain distance therein, a truncated conical member having its smaller end surrounding the inner projecting portion of the inlet pipe and its larger end making a sliding fit with the inside of the barrel, a plurality of spiral vanes secured to said conical member so as to be slidable within the barrel from a position in which the front ends of said vanes substantially coincide with the outlet end of the barrel to produce a relatively short broad flame to a position farther back in the barrel to produce a relatively longer narrower flame, means for effecting such sliding movement from outside the burner barrel, and a casing surrounding the barrel to receive air under pressure and having an annular outlet surrounding the outlet end of the barrel.
